DESIGN FOR A HEEL

William J. Schacht, Miami Beach, Fla., assignor to Schacht Rubber Mfg. Co., Huntington, Ind.,
a corporation of Indiana

Application October 1, 1934, Serial No. 53,451

Term of patent 14 years

To all whom it may concern:

Be it known that I, William J. Schacht, a citizen of the United States, residing at Miami Beach, in the county of Dade and State of Florida, have invented a new, original, and ornamental Design for a Heel, as shown in the accompanying drawing, forming part of this specification.

In the drawing:

Fig. 1 is a plan view of a heel showing my new design.

Fig. 2 is a longitudinal section on the line 2—2, Fig. 1.

I claim:

The ornamental design for a heel, substantially as shown.

WILLIAM J. SCHACHT.
